CLAIM

The ornamental design for a water filter, as shown and described.

DESCRIPTION

FIG. 1 is a perspective view of a water filter showing my new design;

FIG. 2 is a side elevational view thereof, the opposite side being a mirror image;

FIG. 3 is a top plan view thereof;

FIG. 4 is a front elevational view thereof;

FIG. 5 is a bottom plan view thereof; and,

FIG. 6 is a rear elevational view thereof.

FIG.1.

FIG.2.

FIG.3.

FIG.4.

FIG.5.

FIG.6.
